UNITED STATES PATENT OFFICE.

J. WAYLAND KIMBALL, OF NEW YORK, N. Y.

DESIGN FOR ORNAMENTATION OF LEATHER.

SPECIFICATION forming part of Design No. 15,074, dated June 17, 1884.

Application filed March 27, 1884. Term of patent 3½ years.

To all whom it may concern:

Be it known that I, J. WAYLAND KIMBALL, of the city, county, and State of New York, have invented and produced a new and original Design for Leather, of which the following is a full, clear, and exact description.

This design relates to a new and handsome design for ornamentation of leather to be used on furniture and other interior ornaments.

Reference is to be had to the accompanying drawings, forming part of this specification, in which similar letters of reference indicate corresponding parts in all the figures.

Figure 1 is a face view of my newly-designed leather. Fig. 2 is a cross-sectional elevation of the same on the line $x-x$, Fig. 1.

The leather is provided with a series of fields, A, which have their upper surface convex and the under surface concave longitudinally, transversely, and diagonally, whereby gutters B, crossing each other, are formed between the fields. At the intersections of the gutters B imitations of buttons, C, are formed in the leather, the said imitation buttons having a convex top and a concave bottom surface, as shown in Fig. 2. Diagonal grooves d are

formed in the upper surfaces of the fields, the said grooves extending from the imitation buttons partly over the fields. The leather has the appearance of tufted leather used on furniture.

I claim—

1. The herein-described new design for ornamentation of leather, consisting of a series of fields having convex upper and concave bottom surfaces, which fields are separated by gutters, at the intersections of which are imitation buttons that have convex top and concave bottom surfaces, substantially as shown and described.

2. The herein-described new design for ornamentation of leather, consisting of a series of fields having convex upper and concave bottom surfaces, which fields are separated by gutters, at the intersections of which are imitation buttons, the fields having diagonal grooves in their upper surfaces, substantially as herein shown and described.

J. WAYLAND KIMBALL.
